UNITED STATES PATENT OFFICE.

ARTHUR LOPEZ, OF NEW YORK, N. Y.

TYPE-BAR FOR TYPE-WRITERS.

1,120,396.

Specification of Letters Patent.

Patented Dec. 8, 1914.

Application filed March 20, 1914. Serial No. 826,014.

To all whom it may concern:

Be it known that I, ARTHUR LOPEZ, a citizen of the United States of America, residing in New York, in the borough of Manhattan, county and State of New York, have invented certain new and useful Improvements in Type-Bars for Type-Writers, of which the following is a specification.

This invention relates to type bars for typewriters, and has for its object to provide a type bar in which the type is supported in position in a manner to enable the same to be readily replaced by a type of different characteristics, and for this purpose my invention consists of certain novel features and combinations of parts which will be more fully described hereinafter and finally pointed out in the claims.

In the accompanying drawing, Figure 1 is a side view of my improved type bar showing the type support arranged thereon, whereby four different fonts may be used, Fig. 2 is a front view of the type support showing one font of type or one type of one characteristic, Fig. 3 is another view of the type support when the same is rotated to bring the face of the type in operative position corresponding to the front view, but showing a different font of type, Fig. 4 shows the type support arranged to bring a still different font of type into front view, Fig. 5 is a view of the type support arranged to bring the fourth font of type into front view, Fig. 6 is a side view of the type support and arm for supporting the same in somewhat enlarged view than that shown in Fig. 1, Fig. 7 is a view of the other side of the type support with the type arm also in enlarged view, Fig. 8 shows a section taken on line 8-8 of Fig. 6, and Figs. 9 to 12 are side views, and end views of the adjustable fastening means.

Similar characters of reference indicate corresponding parts throughout the various figures of the drawing.

Referring to the drawing, and more particularly to Figs. 1, 6, 7 and 8, the type bar 15 is suitably connected at its end 16 to the typewriter mechanism, whereby the type bar 15 may be properly operated in the usual manner. The type bar proper comprises two plate bars 15 and 32. The plate bar 15 has its upper end provided with a bent portion 18 and extension 19 which is provided with an opening 20. The upper end is also provided with a slot 21, shown clearly in Figs. 6 and 7. A plate bar 32 is secured to the plate bar 15 about midway of its length by means of rivet 22. This plate bar is similar to the upper portion of the plate bar 15, being provided at its upper end with an outwardly bent portion 23 and an upward extension 24. The upward extension has an opening 25 and the body has a slot 26, which latter registers with the slot 21 of the plate bar 15. Movable in the slots 21 and 26 is a fastening device or clamp which preferably consists of a lug 28 having a circular flange 29, and provided with a screw-threaded socket 30, the height of the lug 28 being equal to the depth of the slots 21 and 26, and extending from one side of the member 32 to the farthest side of the plate bar 15. The screw-threaded socket 30 is engaged by a screw-threaded pin 33 secured to a circular flanged portion 34 provided with a slot 35 for use with a screw driver or the like for the purpose of fastening the flanged portion 34 to the flanged portion 29. The lug 28 has parallel walls so as to enable the sides 38 thereof to be adjacent and contact with the parallel walls of the slots 26 and 21. The opening 20 of the plate bar 15, and the opening 25 of the plate bar 32 are engaged by projections 40 and 41 of circular shape, which act in the nature of a shaft and which are secured to and form part of a square-shaped rotary type carrier 43 which at its four sides or faces is provided with type. One side or face 44, namely, that shown in front view in Fig. 2, is provided with type of one font or style, indicated by 45, whereas the face 46 next adjacent thereto, and shown in front view in Fig. 3, is provided with type of a different font or design or characteristic features, indicated by 47. The next and adjacent face 48 is provided with a type of a different font which is indicated by 49, and the adjacent face or fourth face 50 is provided with type indicated by 51 which is of different font or characteristic feature than the other faces. So some of these faces may be provided with the type corresponding to the English letters, and the adjacent face with type corresponding to the German characters, and the type adjacent with the Arabic characters, and the fourth face with Greek characters, or any other characters may be used, as the necessity of the case may require. The member 43 is pro-

vided with eight pins extending therefrom, four being arranged at either side thereof, which pins are arranged, in the embodiment shown in the drawing, at the four corners of the square-shaped member, and these pins 54 engage openings 55 in the extensions 19 and 24, whereby the said pins are locked into the openings and the type support is locked into position.

10 The operation of my improved device is as follows: The type bars comprising plate bars 15-22 are arranged in the usual manner and operated in the usual manner by the well-known type bar operating mechanism, and when it is desired to use one of the four different characters of type, the flanged member 34 is rotated, whereby it is separated somewhat from its socket portion 28, and the members 29 and 34 are moved away 15 from each other, whereby they may be readily brought from the uppermost position of the slots 21 and 26 to the lowermost position of the slots 21 and 26, as shown in dotted lines in Figs. 6 and 8, and thereby 20 the pins 54 may be moved out of the openings 55 of the extensions 19 and 24. By reason thereof, the type carrier may be readily rotated on its shaft portion 40, 41, whereby another face may be brought into 25 operative position with the ribbon and platen. When the desired face is brought into this operative position, the flanged portion 34 is again rotated so as to draw toward it the socket member 28, and thereby 30 move the extensions 19 and 24 in a direction toward each other, so that the openings 55 are engaged by the pins 54 and the type support is thereby locked firmly in position. At the same time, the members 34 and 28 35 are moved from the lower position in the slots 21 and 26 to the upper position, whereby a tight clamping action is provided. It is also very clear that the square-shaped type carrier 43 having the different types 40 thereon, may be entirely taken out of the type bars and replaced by an entirely new set. Thus, by this system of replacing, various and many different uses result. Furthermore, such replacing, when individually 45 done, enables the repairs to be very much facilitated, and such a square-shaped member may be completely taken out and sub-

stituted by a new member, while the member that has been taken out may be readily repaired.

I have shown an embodiment of my invention, but changes may be made therein without departing from the spirit of my invention, as defined in the appended claims.

Having thus described my invention, I claim as new and desire to secure by Letters Patent:

1. A typewriter type bar comprising two plate bars, a rotary type carrier adjustable between said bars in bearings thereof, and a clamp for holding said bars in locked engagement with said carrier.

2. A typewriter type bar comprising two plate bars, a rotary type carrier adjustable between said bars in bearings thereof, and a clamp slidable on said bars.

3. A typewriter type bar comprising two plate bars disposed one on the other and provided with registering slots, a rotary type carrier adjustable between said bars in bearings thereof, and a detachable clamp slidable in said slots for holding said bars in locked engagement with said carrier.

4. A typewriter type bar comprising two plate bars disposed one on the other and provided with registering slots, a rotary type carrier adjustable between said bars in bearings thereof, and a detachable clamp slidable in said slots for holding said bars in locked engagement with said carrier and comprising a flanged screwthreaded socket and a headed screw engaging said socket.

5. An improved type bar, comprising a type bar proper having slots, a clamping device fastened through the slots, a type carrier provided with shafts supported by the type bar proper, type on the face of the carrier, pins on the type carrier, openings in the type bar for engaging the pins on the type carrier for locking the type carrier in position, and means for moving the clamping device in the slots.

In testimony, that I claim the foregoing as my invention, I have signed my name in presence of two subscribing witnesses.

ARTHUR LOPEZ.
